UNITED STATES PATENT OFFICE.

ARTHUR R. ALLARD, OF WILKINSBURG, PENNSYLVANIA, ASSIGNEE TO WESTINGHOUSE ELECTRIC & MANUFACTURING COMPANY, A CORPORATION OF PENNSYLVANIA.

ELECTRODE HOLDER.

Application filed November 12, 1920. Serial No. 423,543.

To all whom it may concern:

Be it known that I, ARTHUR R. ALLARD, a citizen of the United States, and a resident of Wilkinsburg, in the county of Allegheny and State of Pennsylvania, have invented a new and useful Improvement in Electrode Holders, of which the following is a specification.

This invention relates to electrode holders, 10 more especially to holders for electrodes adapted for use in arc welding.

This invention has for its object to provide an electrode holder of simple construction which is adapted to securely hold an 15 electrode in place and provide a good contact between the conducting member of the holder and the electrode.

A further object of this invention is to provide an electrode holder which will allow 20 an electrode to be released by pressure exerted by the operator upon the handle or grip-member of the holder.

In carrying the objects of my invention into effect, I provide a plurality of tubes 25 having a conducting member passing therethrough, the rear end of the conducting member being secured to one of the tubes. A spring member is so secured to the tubes that the tension thereof acts to draw the 30 same toward each other to force the conducting member against an electrode and thus hold it in place.

In the accompanying drawings forming a part hereof and which illustrate a plurality of embodiments of my invention,

Fig. 1 is a view, partly in section and partly in elevation, of an electrode holder constructed in accordance with my invention, and

Fig. 2 is a similar view of the forward end portion of a slightly modified form of holder.

The electrode holder comprises tubes 1 and 2 of insulating material disposed in alinement, a collar 3 having an extension 4 being secured to the rear end of forward tube 1. The collar 3 has a pair of ears 5 which are drawn toward each other by a bolt or similar means 6 to firmly clamp the collar to the tube. A guard or shield 7 is secured to extension 4 of collar 3 and is held thereto by bolts 8.

A spring 9, covered by suitable insulating or covering material 10, has its forward end 11 inserted between guard 7 and extension

4 and is held rigidly in place by the bolts 8. The rear end 12 of spring 9 is secured to a pair of ears 13 of a collar 14 which thus securely holds the spring to the tube 2. The ends of the spring tend to move toward each other, as shown by the arrows 15, and thus to force tubes 1 and 2 toward each other.

One end of a cable 16 is located in the rear end of tube 2, in contact with conducting member 17, a sleeve 18 being provided to connect the cable and conducting member together. A spacer tube 19 is inserted between outer tube 2 and the conducting member 17.

Tube 1 is provided with sleeves 20 and 21 at its respective ends, said sleeves serving as guiding means for the conducting member 17. A metal pipe or tube 22 is inserted between sleeves 20 and 21 and outer tube 1, leaving a space 23 between the conducting member 17 and the pipe 22. Openings 24 are formed at the forward end of the electrode holder to allow of an electrode 25 being slipped into place, the forward end 26 of conducting member 17 being forced against the electrode 25 by the pressure of spring 9 when free to act. The parts are so proportioned that, when an electrode is held in place, the space 27 between the two parts 1 and 2 of the holder is small.

In the embodiment shown in Fig. 2, the forward end of the insulating tube 1 is cut away, as shown, and a metal sleeve 28 is secured to pipe 22. This member may be the ordinary T used in making pipe connections. A plug member 29 is held therein in any suitable manner, as by threads, and an opening 30 is formed in said plug to receive an electrode 25, which is held in place as described in connection with the embodiment shown in Fig. 1.

My electrode holder combines a comparatively simple construction with ease of manipulation. The operator grips the spring 9 and the tube 2 very lightly when he is manipulating an arc, the construction being such that he cannot exert considerable pressure thereon without releasing the electrode. Being thus compelled to grip the holder very lightly, the operator may more readily control the arc and may work a longer time without fatigue.

It is apparent that various changes in the details of construction of my electrode

holder may be made without departing from the spirit of my invention. I desire to claim my invention broadly except as limited by the claims appended hereto.

5 I claim as my invention:

1. In an electrode holder, a conducting member, means for connecting a cable thereto, and a handle comprising a spring constituting gripping means for said holder.
2. In a holder for engaging an object, a pair of telescoping object-engaging members, the outer telescoping member having a portion extending beyond the inner member and having shoulders adapted to grip the object when said outer member is drawn backwardly over the inner telescoping member, said inner telescoping member extending back farther than said outer telescoping member, and gripping means comprising a bowed spring connected between the rear ends of the telescoping members and biased to draw the outer telescoping member backwardly, whereby a predetermined pressure on the gripping means will release the held object.
3. An electrode holder comprising a handle portion, a conducting member secured therein, a sleeve disposed around said conducting member, means in said sleeve for receiving an electrode and a spring connected to said sleeve and handle which con-

stitutes a part of the handle grip, said sleeve and handle being axially movable to effect engagement of said electrode and conducting members.

4. An electrode holder comprising a body portion formed in two parts, a conducting member secured in one of said parts and extending into the second of said parts, and a spring for connecting the said parts and serving to draw them toward each other, said spring constituting the handle of said electrode holder.

5. An electrode holder comprising a plurality of tubes, a conducting member secured in one of said tubes and extending into a second tube, a spring handle secured to said tubes and serving to draw them toward each other, said second tube having a laterally disposed opening in one end.

6. An electrode holder comprising a plurality of tubes, a conducting member secured in one of said tubes and extending into a second tube, a spring handle secured to said tubes and serving to draw said tubes toward each other, said spring handle being insulated from said conducting member, and said second tube having a lateral opening in one end.

In testimony whereof, I have hereunto subscribed my name this 28th day of October, 1920.

ARTHUR R. ALLARD.
